3 Claims. (Cl. 33—80)

ABSTRACT OF THE DISCLOSURE

A device is disclosed for attachment to a T-square blade so as to cause the T-square head to be pressed firmly against the working edge of the T-square. The device maintains the working edge of the T-square blade in alignment with the working edge of the drawing board. The upper surface of the device can be constructed so as to form a tray for the storage of supplies such as pencils and erasers. When the device is attached to a modified adjustable-head T-square, the T-square can be tilted upward or downward.

The common T-square, which has long been in widespread use as a drafting instrument, has the disadvantage of being unstable and unreliable for drawing parallel lines, mainly because the accuracy of the parallel motion of the T-square blade is dependent upon the alignment of the head of the T-square with the edge of the drawing board. This requires the draftsman to use one hand to press the T-square head firmly against the board.

Various modifications in the construction and arrangement of the boards and T-squares have been devised in attempts to overcome this disadvantage. Such modifications have either not worked satisfactorily, or resulted in expensive equipment. Drafting machines which are in common use in industry, for example, are beyond the price range of the average drafting student or draftsman.

It is an object of the present invention, therefore, to provide a novel T-square stabilizer.

It is another object of the present invention to provide a T-square stabilizer that is simple in construction, easy to manipulate, and inexpensive to manufacture.

It is still another object of the present invention to provide a T-square stabilizer that can be conveniently attached to the blade of a T-square so as to support it resiliently on a drawing board.

It is yet another object of the present invention to provide a T-square stabilizer that can sustain the T-square on a drafting board so as to relieve the draftsman of all care in connection with the support of the T-square head against the edge of the drafting board.

It is yet another object of the present invention to provide a T-square stabilizer that is suitable for use with a T-square having an adjustable head.

According to the preferred embodiment of the present invention, a stabilizer for converting a T-square into a self-aligning straightedge comprises a body member having a slot through which passes screw means for fastening the stabilizer to the existing hole in the blade of a conventional T-square. A roller is spring-coupled to the body member and exerts pressure on an edge of the drawing board, thereby causing the head of the T-square to be pressed firmly against the opposite edge of the drawing board.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings, in which:

2

FIGURE 1 is an isometric view of a T-square stabilizer according to the present invention.

FIGURE 2 is a partly-sectional side view of the T-square stabilizer of FIGURE 1, showing in detail the means by which it is connected to the T-square.

FIGURE 3 shows a different embodiment of the present invention.

FIGURE 4 is a partly-sectional side view of the stabilizer of FIGURE 3.

Turning now to the drawings, FIGURE 1 shows T-square stabilizer 11 mounted upon and fastened to blade 13 of T-square 15 by means of knurled thumb nut 17. T-square blade 13 is fastened to T-square head 19 by screws 21. T-square 15 is shown resting upon drawing board 25, with head 19 supported firmly against edge 27 of board 25.

T-square stabilizer 11 has a body member 31, which can be manufactured as an extruded section having tubular edges 33 and 35, and upright ends 37 and 39. Tubular edges 33 and 35 and ends 37 and 39, being upright and above the flat central portion 40 of body member 31, cooperate so as to form an enclosed tray therewith upon the upper surface thereof. This tray can be used for storing pencils, erasers, etc.

Slot 41 runs along the flat central portion 40 of body member 31 and extends along a majority of the length thereof, parallel to and equidistant from tubular edges 33 and 35. Slot 41 is used in combination with fastening means to facilitate adjustment of the tension applied to the T-square and also to make it possible to use stabilizer 11 with T-squares of various lengths.

FIGURE 2 shows how screw 43 passes through light-gauge finishing washer 45, hole 47 in blade 13, and slot 41, and mates with thumb nut 17. Stabilizer 11 is securely attached to T-square blade 13 by means of screw 43. When thumb nut 17 is loosened, stabilizer 11 is free to slide along blade 13 for the length of slot 41. Tape strip 49 is made of a cork and rubber composition and has an adhesive backing along surface 51 so that it will adhere to the bottom of body member 31. Tape strip 49 increases the friction between stabilizer 11 and blade 13.

Rod-like shafts 53 and 55 fit within tubular edges 33 and 35, respectively, and are joined together by cross-tie member 57, so as to be U-shaped. Shafts 53 and 55 could be manufactured as a single U-shaped member. Nylon roller or wheel 59 is free to rotate on axle 61, which is mounted upon member 57. Roller 59 lies in plane parallel to flat central portion 40.

The end 63 of each rod-like shaft is coupled to the extreme end of the tubular edge associated therewith, by means of a tension spring 65. The tension springs 65 will pull shafts 53 and 55 within tubular edges 33 and 35, respectively, until member 57 abuts against end 39. The method of using the T-square stabilizer 11 will now be described.

The draftsman unscrews thumb nut 17 and removes screw 43 and washer 45. The washer 45 is then placed in axial alignment with hole 47 on the bottom surface of T-square blade 13 and screw 43 is inserted therethrough from the bottom. Stabilizer 11 is positioned upon the top surface of T-square blade 13 so that screw 43 extends through slot 41. Stabilizer 11 is then moved linearly along the top surface of T-square blade 13 until it is positioned such that the forces exerted by the springs 65 upon shafts 53 and 55 pull roller 59 firmly against the edge 71 of drawing board 25.

Thus, the position of stabilizer 11 with respect to blade 13 depends upon the width of drawing board 25. As a consequence of the configuration of stabilizer 11, it can be used with any drawing board and T-square combination so long as the length of blade 13 projecting from

head 19 is not in excess of the width of drawing board 25 by more than approximately the radius of wheel 29, and not less than the width of board 25 by more than the maximum distance to which wheel 59 can be extended.

Thumb nut 17 is used to fasten stabilizer 11 securely to blade 13. When blade 13 is placed upon drawing board 25, it will be separated therefrom by the thickness of washer 45. It is important, therefore, that washer 45 be as thin as possible, and that the surface of washer 45 in contact with board 25 be as smooth as possible to mitigate friction therebetween. The head of screw 43 should be recessed within the central hole of washer 45, so as not to be in contact with board 25. If desired, a countersunk hole can be drilled through blade 13, and screw 43 can be used without washer 45, so that the head of screw 43 will not protrude beyond the surface of blade 13.

The pressure exerted by roller 59 against edge 71 of board 25 will be transmitted through blade 13 to head 19, and will cause head 19 to be pressed firmly against board 25. The T-square 15 will remain in parallel alignment as 20 it is moved along the edges of board 25. The draftsman will be relieved of all care in connection with the support of the T-square head against the edge 27 of the drafting board 25.

The described stabilizer is adjustable by means of slot 25 41 and thumb nut 17 so that stabilizer 11 can be used with T-squares of various lengths, and can also be adjusted for a variety of different tensions. T-squares are conventionally manufactured with holes in the extreme end of the blade, for hanging on nails, etc., and stabilizer 11 can 30 be used with the existing hole. Thus, the stabilizer 11 can be easily attached to any common T-square by means of a single stud or screw and nut combination.

Slot 41 makes it feasible to vary the spring tension on roller 59. The draftsman can adjust the tension on roller 35 59, so that T-square 15 can be moved easily for sketching. The tension can then be changed so that T-square 15 will be firm and steady for lettering with a lettering guide, as well as adjusted to moderate tension for ordinary drawing. By using the described T-square stabilizer, the 40 draftsman will be able to obtain most of the advantages of a drafting machine for a fraction of the cost.

FIGURES 3 and 4 show another embodiment of the present invention in which three countersunk holes are drilled into the end of blade 71 of the adjustable-head 45 T-square 73, along a line perpendicular to the edges thereof. One hole is in the middle and the other two holes are equidistant from the edges of blades 71. Body member 75 of T-square stabilizer 77 is an extruded section and is fastened to blade 71 by screw 79, which passes through 50 hole 81. Hole 81, being countersunk, permits the head of screw 79 to be recessed within blade 71, and not to protrude below the bottom thereof.

When the T-square 73 is used as a conventional T-square, the central hole is used. When the T-square 73 55 is tilted upward, as shown in FIGURE 3, the bottom hole 81 is used, as shown, so that the end of stabilizer 77 does not extend beyond the upper edge of T-square blade 71, which might interfere with the use thereof for drafting. When T-square 73 is tilted downward, the upper hole is 60 used and stabilizer 77 is tilted upward.

The significance of the described embodiment is that in the case of an adjustable-head T-square, it is important to align the pivot point 83 in the head 85 with the point of contact between roller 87 and board 89. Thus, the more 65 closely line 93, which passes between those points, is aligned perpendicularly to side 91 of board 89, the more stable the T-square will be.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. A stabilizer for a T-square having at least one hole in an end of the blade thereof, comprising:

- (a) a main-body member having a substantially flat surface lying in a first plane, a recessed surface opposite said flat surface for supporting objects thereon, and a linear slot passing through said body member and extending along a major portion of the length thereof;
- (b) fastening means coupled to said body member for securing said body member to said T-square blade through said slot and said hole in said blade; and
- (c) support means for coupling said blade to an edge of a drawing board, said stabilizer causing the head of said T-square to be pressed firmly against the opposite edge of said board when so coupled, said support means including a single wheel-like roller means coupled to said main-body member by spring means, said roller means being rotatable in a second plane parallel to said first plane, and extendable linearly along said second plane, said roller means being coupled to said spring means by a pair of rod-like shaft means, each shaft means fitting slidably within a tubular edge of said body member, and said recessed surface having enclosing sides formed by said tubular edges and upright end members.

2. Apparatus as defined in claim 1 in which said head of said T-square is pivotable with respect to said T-square blade, which has three countersunk holes drilled therein linearly across the distal end of said blade for attachment of said stabilizer therethrough.

3. A stabilizer for converting a T-square into a self-aligning straightedge, comprising:

- (a) a main-body member having a substantially flat surface lying in a first plane, and a linear slot passing therethrough and extending along a major portion of the length thereof, the blade of said T-square having a plurality of holes provided transversely across the distal end thereof;
- (b) fastening means coupled to said body member for securing said body member to said T-square blade through said slot and one of said plurality of holes in said blade; and
- (c) support means for coupling said blade to an edge of a drawing board, said stabilizer causing the head of said T-square to be pressed firmly against the opposite edge of said board when so coupled, said support means including rotatable roller means lying in a second plane parallel to said first plane, said roller means being coupled to said main-body member by spring means.
